UNITED STATES PATENT OFFICE.

ARTHUR H. PITNEY AND JACOB W. OGDEN, OF STAMFORD, CONNECTICUT, ASSIGNEES,
BY MESNE ASSIGNMENTS, TO PITNEY-BOWES POSTAGE METER COMPANY, OF
STAMFORD, CONNECTICUT, A CORPORATION OF DELAWARE.

MACHINE FOR PRINTING VARIOUS DENOMINATIONS OF POSTAGE ON MAIL MATTER,
ETC., AND REGISTERING AMOUNT THEREOF.

Application filed March 10, 1923. Serial No. 624,223.

- This invention relates to machines for impressing stamps or the like upon envelopes, cards, and the like, and simultaneously registering the amount printed, and is in particular an improvement in machines of the type shown in the Pitney Patents #1,273,793 dated July 23, 1918; Reissue #14,916 dated July 13, 1920; and #1,370,668 dated March 8, 1921.
- 10 Such machines are designed for use by persons, firms, or corporations having large numbers of letters to mail; and enables such user to purchase any desired amount of prepaid postage from the Government, and then print such postage, from time to time, in any denomination desired, until the amount of postage paid for is exhausted, whereupon the machine will become automatically locked so that no further stamps can be 20 printed thereby.
- The object of the present invention is to provide novel means whereby any one of a plurality of denominations of stamps, or the like, may be printed as desired, and the amount of each stamp (of any denomination) be automatically registered in the machine without requiring the use of a plurality of interchangeable meters, such as described and required in the above mentioned 30 Pitney patented machines.
- More particularly the present invention is designed to print "metered mail" indicia of different denominations on letters, cards, etc., and register the amount of postage used 35 by means of only one printing die and only one meter. The die has a plurality of printing surfaces each representing a different denomination of stamp and any one of such surfaces may be operatively positioned at 40 the will of the operator, to receive ink and produce imprints. The turning of the die to bring the desired printing surface to operative position through suitable mechanism automatically changes the relation of the 45 gearing between the die and meter, in such a manner that the meter will record in terms of dollars and cents the face value of the imprint produced by that particular surface of the die which is in operative position. The adjusting of the die for different surfaces also automatically changes (through suitable mechanism) the index and 50 ink devices, so that ink of the desired dis-
- tinctive color corresponding to the denomination engraved on the face of the die will 55 be supplied to that surface when said surface is brought into operative position.
- This invention obviates the necessity of the user carrying in stock a number of "metered mail" meters containing dies of denominations which he infrequently wishes to use.
- In general, the output and operation of our present machine is substantially the same as that of the machine described in the Pitney Patent #1,370,668, that is, the complete machine will seal, print, and stack envelopes for mailing, and register the amount of postage printed thereon by means of a recording member or meter, but in the above mentioned Pitney patent a separate meter containing a printing die is required for each and every denomination of stamp, while in our present invention only one printing member and only one meter is required. The die has a plurality of faces engraved with indicia representing different denominations; and the die can be adjusted so that any one of its faces can be brought 70 into operative position. And the present invention further provides means whereby if desired each different denomination of stamp may be printed in its own distinctive color; and to this end the invention further 75 includes novel means whereby when the die is shifted so that the impression therefrom will give a stamp of a certain denomination, the proper color inking devices will be brought into position to cooperate with the face of the die so that the stamp printed thereby will be of its own proper distinctive color.
- The invention further provides means whereby when the die is adjusted to change the denomination of the stamp which will be printed thereby, the register actuating devices will be automatically adjusted so that the register will be actuated in exact accordance with the denomination printed by the die, for each operation of the die. For example, if the die is adjusted to print a 1¢ stamp for each operation of the machine the register would register only one unit at each operation; if the die is adjusted to print a 2¢ stamp the register would register two units for each operation of the ma-

- chine; and if the die is shifted to print a 5¢ stamp the register would register five units for each operation of the machine, etc. The machine is so constructed that it cannot 5 be made to print a stamp of high denomination while the registering mechanism registers a lower denomination, or vice versa, but the exact amount of each stamp printed will be registered.
- 10 In the present machine all of these adjustments, except that of shifting the die itself (which is manually performed) are automatically performed by mechanisms in the machine.
- 15 The machine is further provided with means for automatically preventing operation of the machine unless the meter is in proper position therein; means for automatically stopping the effective operation 20 of the machine when a predetermined amount of prepaid postage has been exhausted; and other safety locking means as hereinafter described, as set forth in the patents above referred to; so that it would 25 be impossible for the user of the machine to cheat the Post Office Department, or for the user's employees to effectively operate the machine without a record of such operations being made by the registering mechanism.
- 30 Other objects and advantages of the invention will be hereinafter set forth. We will explain the invention with reference to the accompanying drawings which illustrate one practical embodiment of the invention, and an understanding thereof will enable others to adopt and use the invention for various purposes; however, it is capable of changes in form, construction, and combinations of parts, within the scope of the 35 claims, which set forth the essentials of the invention and the novel features of construction and novel combinations of parts for all of which protection is desired.
- 40 The machine illustrated in the drawings is designed to print and register stamps of the like of three denominations, to wit, 1¢, 2¢ and 4¢, and the register actuating gear ratios are calculated accordingly; but other denominations could be used by making a corresponding change in the ratios of the gears 45 controlling the register, so that the invention is not restricted to the specific denominations illustrated. Neither is it restricted to a three-face printing member as such member 50 could be provided with two, four, or more printing faces, the register actuating gears being correspondingly changed.
- 55 In said drawings:

The machine to which the invention is applied is preferably constructed (except as 100 to the parts hereinafter referred to) as described in Pitney's Patent #1,370,668, dated March 8, 1921, and has a feed table, envelope sealing devices, and feed rollers (not shown herein) for directing the letters to and past 105 the rollers 21, 22, Fig. 1, by which the envelopes are directed on past the impression roller 137 and the printing member 238, hereinafter referred to, and the letters after 110 being postmarked are discharged between the rollers 108, 109, in front of a stacker wheel (not shown) by which they are stacked in the usual manner on a table or rack, not shown, but as described in the aforesaid 115 Pitney patent. The rollers 21, 22, 137, 108, 109, shown in Fig. 1, employed for permitting the printing member to operate once for each letter fed through the machine may be 120 constructed and operated substantially as described in said patent, and form no particular part of the present invention. Therefore we have not deemed it necessary to illustrate nor describe same in detail herein.

We have herein called the object being operated upon a "letter", by which we intend to include any object such as checks, 125 cards, small packages, etc., upon which the machine is adapted to operate, as we do not intend to limit the invention to machines for operating on mail matter only. We also 130

use the word "Stamp" to designate the character of the impression surface of the printing member, but use the word "Stamp" merely as a descriptive term, and not as limiting the printing member to any particular kind or denomination of postage stamp, as the printing member might be readily adapted for printing tickets, vouchers, etc., of various kinds and denominations, and by 10 the use of the word "Stamp" we do not intend to restrict the invention to use on mail matter only.

In the present invention the printing member 238 carries an adjustable printing die 240 having a plurality of printing faces, and adjacent to the printing member is an inking member preferably carrying a set of inking devices, and which is automatically adjusted so as to supply the proper color 20 of ink to the related printing surface of the die by and with the adjustment of the printing die on the printing member, as hereinafter explained.

Also adjacent the printing member 238 is an adjustable register actuating mechanism which, at each operation of the printing die, operates the register, and devices are provided by which the extent of operation of the register is automatically controlled and 30 adjusted by the adjustment of the printing die surface; so that the register will be operated in accordance with the denomination of the stamp actually printed by the die at the printing point. Also, a removable meter 35 is preferably provided containing the registering mechanism; and suitable safety controlling devices are employed whereby the machine cannot be operated unless the removable meter is properly positioned in the 40 machine and whereby, after a predetermined number of stamps has been printed, the meter is prevented from being effectively operated; and other minor safety devices are provided, as hereinafter referred to.

45 The adjustable printing member.

As shown in Figs. 1, 2, 3, 8, and 9, the printing member comprises a revolvable casting having a disk-like portion 238, and a hub 238^b by which it is connected to the upper end of a vertical shaft 237 which extends through box 201 mounted on the table top 200 of the stand, carrying sealing, printing, and stacking mechanism similar to that 50 shown in our aforesaid Pitney patent. The upper end of the shaft 237 is journaled in an overhead bearing plate 203 secured to the top of the box 201 by bolts 204^a extending through spacing sleeves 204. This shaft 237 55 extends into and practically through the box 201 and its lower end is journaled in a bearing 201^a and connected by a suitable clutch hereafter described with the driving mechanism below the top 200, as hereafter 60 explained.

The printing die 240 is mounted on a stud shaft 241, parallel with the hub 238^b, and journaled at the lower end in part 238^b of disk 238 and an arm 238^a projecting from hub 238^b above the disk. The die 240 is 70 approximately triangular in cross section, Fig. 9, and its side faces are curved instead of planes. The die can be turned on its axis so as to bring any one of its curved faces into a position (indicated at 240^p in Fig. 9) 75 where it will form a segment of a cylinder whose axis is the center of shaft 237. Therefore when the printing member 238 is revolved by shaft 237 the face 240^p of the die 240 would contact with the impression roller 80 137 (Fig. 9) and if properly inked will make an imprint on a letter interposed between the die 240 and impression roller 137.

The die 240 is provided with key ways 241^a engaging keys on shaft 241 (Figs. 8 85 and 9) so that the die 240 is caused to revolve with shaft 241, but said shaft may be moved axially of the die. A cupped bushing 241^b (Fig. 8) is slidably fitted on the upper end of shaft 241 so that it can turn with 90 shaft 241 while permitting axial movement of the shaft. A knurled knob 242 is secured by means of pin 242^a to the upper end of bushing 241^b. A spring 241^c is placed between the bushing 241^b and the knob 242 95 around the shaft 241, and tends to force the shaft 241 upwardly and normally hold it raised as in Fig. 8.

On the lower end of shaft 241 is a disk 243 adapted to fit into a recess in the lower part of printing member 238, said disk being provided with a tubular extension or hub 243^b extending upwardly therefrom upon the lower end of which is loosely mounted a plate 244. Above disk 244, and around the upper end of hub 243^b and shaft 241, and contacting with the walls of the recess, is a sleeve 245 pinned to shaft 241 and extending over the hub 243^b of the disk 243, serving to hold the plate 244 in place on the 100 disk 243 and causing said plate 244 to move axially with the shaft 241 though said plate does not revolve with shaft 241.

From the lower face of disk 243 project three pins 243^a which are equally spaced 115 apart on a circle whose center is the center of the shaft 241, said pins being firmly pinned to the disk 243.

Plate 244 has a free running fit on the hub 243^b, and to this plate 244 are fastened three upwardly projecting pins 244^a which are equally spaced apart and equi-distant from the center of shaft 241. These pins 244^a pass entirely through the disk 238 and project a short distance above it, and are adapted to engage three similarly located holes in the bottom of the die 240 (see Figs. 8, 9) to hold the die in adjusted position 125 during the printing operations.

Shaft 247 (Fig. 8) is journaled in the 130

top plate 201^a of the box 201 directly in line with the shaft 241 when the latter is in "rest" or normal position. On the upper end of shaft 247 is fastened a disk 246; and to its lower end is fastened a gear 248.

The disk 246 is seated in a suitable recess in the top plate 201^a so that its upper face is flush with the top of said plate (Fig. 8). Disk 246 is provided with three holes 246^a which are exactly opposite the three pins 243^a of the disk 243 (when the parts are in normal position) so that if shaft 241 be pushed down by pressing on the knob 242, the three pins 243^a will enter the related holes 246^a in disk 246.

Three shouldered pins 249 are mounted in the top plate 201^a of box 201 below the disk 246, the pins 249 being exactly in line with pins 243^a and holes 246^a when the die is in normal rest position. The pins 249 are normally pushed upward by springs 249^a held in place by screws 249^b (as shown in Fig. 8) and when pins 249 engage the holes 246^a in disk 246, they prevent any turning of the disk 246, shaft 247 and gear 248; and will also prevent any turning of shaft 241 on its own axis but will not prevent rotation of the printing member 238.

By pressing down on the knob 242 the shaft 241, disks 244, and 243, can be moved downward, and the pins 244^a withdrawn from the holes in the die 240, which can then be turned with shaft 241 to bring any desired printing surfaces of the die to the position indicated at 240^b in Fig. 9.

When shaft 241 is depressed as described, the pins 243^a of disk 243 will enter the holes 246^a in disk 246 and push ahead of them the three pins 249, until the tops of pins 249 are clear of the under side of disk 246, and the lower ends of the pins 243^a are flush with the under side of disk 246, which disk 246 is then free to be revolved with and by the turning of the knob 242 on shaft 241. After the turning has progressed a short distance, the downward pressure on knob 242 may be relaxed as the holes in the die 240 will then be out of register with pins 244^a and no upward movement of the shaft 241 can take place until they again register. When the die 240 has been turned through 120 degrees however, the holes and pins will again register and the spring 241^a, aided by the springs 249^a, will raise the whole unit, shaft 241 and parts carried thereby, and the pins 244^a will again enter holes in die 240, and the pins 243^a withdrawing from the holes 246^a in disk 246 are followed up by the pins 249. Thus, die 240 and gear 248 are both locked in the new adjusted position.

Knob 242 can only be pushed down when the die shaft 241 is directly in line with shaft 247, as at any other part of its revolution the pins 243^a would encounter the top of the disk 246.

The disk 238 of the printing member is provided with a downwardly projecting flange 238^a which extends close to the top of the box 201 and prevents access to the disk 246 and stop pins 249 when the die 240 is not in the "rest" or normal position.

The inking mechanism.

Beside the printing member is mounted the inking member. In the construction shown in Figs. 1, 2, 3 and 7 the inking member comprises a revolvable casting 124 having a hub 124^a and three radial arms 124^b on each of which is mounted a felt inking roller 123. As shown, each inking roller is mounted on a spindle 123^a which is supported on an adjustable member 123^b which is pivoted on the arm 124^b by a pin 123^c, which extends through the arm 124^b and has a disk-like head 123^e on its lower end which is adapted to ride on an annular boss 201^b formed in the top 201 of box 200 directly under the path of the ink rollers, said boss being provided with three equally spaced depressions 201^c into which the heads 123^e of the ink roller pivot pins 123^c are allowed to drop at each indexing of the bracket 124. This seating of the pivot heads 123^c in the depressions of the box 201^b absorb the shock of the impact of the die 240 against the ink rollers 123 and protect the gear train inside the box from undue strain. The individual inking roller and its support, with the exceptions explained, may be constructed and operated substantially as explained in the aforesaid Pitney patent and as we do not claim the particular construction of the inking mechanism herein we think it is unnecessary to describe the same more in detail. Each of the ink rollers 123 is charged with ink of a distinctive color to suit the denomination of the postage stamp indicia engraved on the several faces of the die 240.

The hub 124^a of the printing member is splined on a vertical shaft 255, the upper end of which shaft is journaled in the plate 203 and the lower end in the top plate 201^a (see Fig. 7) of the box 201, shaft 255 being parallel with the shaft 237.

The shaft 255 is provided with two keys, running its entire length and on its lower end is a gear 254, said gear 254 and bracket 124 being further secured by set screws, as shown in Fig. 7. The upper end of shaft 255 is provided with a sleeve 255^a, which enclosing the key acts as journal for the shaft in the overhead bearing plate 203, the lower end of shaft 255 being fast to the hub of a gear 254 which hub is journaled in the top of box 201.

A spring 255^a is placed around the shaft 255, and between the top of hub bracket 124^a and the bottom part of the sleeve 255^a, and said spring normally pushes the inking member 124 downward. As both member 124

and sleeve 255^a revolve with shaft 255, the spring 255^a is not affected by the turning of member 124. The spur gear 254 on the lower end of shaft 255 operates the inking member 124 and is geared to the spur gear 248 on the shaft 237 operating the printing member by means of a series of intermediate spur gears 253 and 250 (see Fig. 5) which are mounted on studs 253^a and 250^a attached to a 10 frame 205 secured in the box 201.

These gears are so arranged that when the shaft 241 is turned to adjust the printing faces of the die 240 (as above described) the gear 248 is turned by and with shaft 241 15 and consequently through the intermediate gears 250, 253, gear 254 and shaft 255 may be turned operating the inking member 124 so that the proper inking roller 123 will be brought into position to coact with that die 20 surface which is brought into operative position and thus will supply the distinctively colored ink to its related die surface.

At each setting or adjustment of the die 240, the ink roller bracket 124, and pivot 25 heads 123^a must be lifted clear of the depressions 201^a in the boss 201^b, in order that it can be revolved. For this purpose a lever 256, Fig. 7, is introduced in the interior of the box 201. Lever 256 is pivoted at its center in the stud 257, one end extending under the lower extremity of shaft 255, the other extending an equal distance in the opposite direction, terminates under a plunger 258, which passes through the top of box 201 and 30 is provided with a knob 259 on its upper end. By pressing down on the knob 259 the ink roller bracket 124 is lifted against the thrust of the spring 255^a, Fig. 3, releasing the pivot heads 123^a from engagement with the depressions in boss 201^b and allowing the bracket to 40 be turned. The gear 254 is made with an extra wide face so that this lifting operation will not carry it out of mesh with the gear 253 of the index gear train.

45 *The variable register actuating mechanism.*

The machine shown is designed to print stamps of varying denominations, and to register the amount or value of any and each 50 stamp printed by it. Therefore we provide means whereby the amount of each stamp will be registered. In the said machine, we use a single register for all the various stamps, and have provided means whereby whenever 55 the die is shifted to change the denomination of the stamp to be printed, the register actuating devices will be correspondingly adjusted so that the amount of such stamp will be registered by the register. For this purpose we provide novel automatically adjusted register actuating mechanism whereby a variable extent of motion will be imparted to the units wheel of the register in accordance with the particular denomination 60 of the stamp which is to be printed.

As shown in the drawings (Figs. 3, 4, 5) a beveled gear 209 is splined to shaft 237 and engages a beveled gear 210 on a shaft 211 journaled in transverse members 205^a, 205^b, and 205^c, of a frame 205 secured in the box 70 201.

Shaft 211 is shown as provided with two keys 211^a (preferably integral parts of the shaft) running its whole length and on opposite sides. Sleeves 211^b, which are key 75 slotted with a cylindrical outside form are provided as journals for the shaft 211 at places where it has bearings in the frame 205. The gearing is such that the shaft 211 makes one revolution for each revolution of 80 the shaft 237 and printing member 238.

A shaft 212, Figs. 12, 13, and 5, is arranged beside and parallel with shaft 211, and journaled in the members 205^a, 205^b, and 85 is provided with collars 215 to prevent longitudinal movement of the shaft. Shaft 212 is preferably provided with short keys 212^a about midway between the members 205^a and 205^b (Fig. 4).

Motion is communicated to shaft 212 from 90 shaft 211 by means of either one of three pairs of gears 216—216^a, 217—217^a, or 218—218^a, Figs. 3, 4, 5 and 6. Gears 216, 217, and 218 are slidably mounted on shaft 211 and their mating gears 216^a, 217^a, and 95 218^a are slidably mounted on shaft 212.

Each of the gears 216—216^a, 217—217^a, 218—218^a, is key slotted to fit easily over the keys 211^a and 212^a on their respective shafts so that said gears may be slid axially 100 on their respective shafts.

The keys 212^a, Fig. 4, are only long enough to engage one of the gears 216^a, 217^a, or 218^a on shaft 212, but all the gears 216, 217 and 218 are engaged with the keys 211^a on shaft 105 211. Consequently, although all six gears will be revolved when shaft 211 is turned, only the one gear (218^a or 217^a or 216^a) that is engaged with the keys 212^a on shaft 212 110 will impart motion to shaft 212, the other two gears merely turning idly upon it.

Means are provided, as hereinafter described, for sliding the entire set of gears axially on the shafts 211 and 212, so as to cause the proper gear 216^a, or 217^a, or 218^a 115 to drive shaft 212.

The object of shifting the gears is to vary the extent of rotation of shaft 212 relative to the rotation of shaft 211. The shaft 211 always makes one revolution for each imprint, regardless of the denomination being printed, but the extent of rotation of shaft 212 which actuates the meter must vary with the denomination of each different stamp printed, in order to advance the registering mechanism proportionately to that denomination. For instance, the angular travel of the shaft 212 must be four times as great to record a 4¢ imprint as it is to record a 1¢ imprint. This shaft 212 extends beyond the 120 125 130

wall 205* (Figs. 3 and 12) and has a coupling member 213 on its end which projects through an opening in the outer end wall of the box 201, as indicated, and is adapted to engage an opposed clutch member 306 on the register-actuating shaft in the meter 300 hereinafter referred to.

- The ratios of the teeth in the three pairs of shifting gears are selected to satisfy such requirements. The driving gear 216 in the example shown has half the number of teeth of its mating gear 216^a and when gear 216^a is engaged with keys 212^a on shaft 212, it will cause shaft 212 to make $\frac{1}{2}$ revolution to one revolution of shaft 211. The driving gear 217 has the same number of teeth as its mating gear 217^a, and when properly positioned over the keys 212^a will cause shaft 212 to make one revolution for each revolution of shaft 211. And the driving gear 218 has twice as many teeth as its mating gear 218^a and when engaged with keys 212^a will cause shaft 212 to make two revolutions to each one of shaft 211.
- The meter or registering mechanism is so constructed that it will register one cent for each half turn of the shaft 212; it will therefore register two cents for a full turn; and four cents for two turns of shaft 212.
- As shaft 211 always makes one complete revolution for each printing operation, and as shaft 212 is always advanced in multiples of $\frac{1}{2}$ revolution whichever gear is engaged, and as shaft 212 is provided with two keys 212^a on opposite sides, and as each gear is provided with two key seats 212^a on opposite sides, it follows that the key seats in the gears 216^a, 217^a, and 218^a will be in alignment ready to slide over the keys 212^a at the end of each operation of the machine.

With some variations of denominations of stamps it may be necessary to alter the center distance of shafts 211 and 212, and it may also be necessary to gear the shafts so that the meter will record one unit for some other fraction of a turn of shaft 212; say $\frac{1}{4}$ turn or $\frac{1}{6}$, instead of $\frac{1}{2}$, in which case it would be necessary to spline shaft 212 so that it would have four or six keys 212^a in order to meet the service conditions; but such changes would be readily made by the designer or mechanic, and would obviously be within the scope of the invention.

- The sets of gears may be slid longitudinally of the shafts 211 and 212 by any suitable means. As shown in Figs. 3 and 5, a U-shaped gear shifting frame 206 is slidably mounted on the shafts 211 and 212; and is provided with key slotted bushings 206^a fitted in the openings in its sides through which the shafts 211 and 212 pass, as indicated in Figs. 3 and 6. The gear shifting frame is of such width that the bushings 206^a make a close running fit with the outer ends of the hubs of gears 218, 218^a, and 216,

216^a, so that if the gear shift frame 206 is moved longitudinally of the shaft, the sets of gears 216—216^a, 217—217^a, and 218—218^a will be moved with the frame 206. One end of a link 252 is pivotally connected to a stud 206^b on frame 206 and the other end of said link is pivotally connected to a crank pin 251^a on a gear 251 which is journaled on a stud 251^b on the frame 205, adjacent the intermediate gear 250 and meshing therewith. The gear 251, as shown in Fig. 5, has the same number of teeth as gear 248, and consequently when the gear 248 is turned by the adjustment of the printing die 240 (as above explained), the gear 251 will be correspondingly turned. Thus when the die 240 is turned on its axis to bring any of its three faces into printing position, the gear shifting frame 206 will be moved by link 252 correspondingly to one of its three positions, corresponding to the die faces, and bring the proper gear 216^a, or 217^a, or 218^a into engagement with the keys 212^a on the shaft 212, thereby assuring the registering of the correct amount for each stamp printed by the die 240.

The meter.

The shaft 212 might be directly connected with the units wheel actuating shaft of the registering mechanism. In the machine shown we prefer to place this registering mechanism in a so-called "meter", constructed and adapted to operate substantially as shown and described in the afore-mentioned Pitney patents, so that the machine can be used for the purposes set forth therein. This "meter" casing is shown at 300 in the drawings and is removably supported upon a bracket 202 which is secured to the under side of the table 200 and projects beyond the outer end of the box 201, and has side flanges 202^a, as shown in Fig. 5, on its opposite sides adapted to engage the flanges on the sides of the meter casing 300, substantially as described in our patent.

The regulating mechanism in the meter consists of two counting units A and S (see Fig. 14) of the geared type, mounted in the frame and driven by the same gears. Counter A, starting at zero, adds one unit for every cent represented by the printed indicia delivered by the machine. Counter S, being "set" or "charged" to the highest number in its range, will subtract one unit for every cent's worth of impressions used, until the count reaches zero when by actuating certain locking devices it prevents the forward motion of the meter pin 208 (Fig. 3) thereby rendering the machine inoperative, besides locking its own driving mechanism.

The counting units need no description as they are of the well known geared type, the unit wheel being the only directly driven wheel of the series, motion being conveyed

from units to tens, tens to hundreds, etc., by "Geneva stops" or intermittent gears.

The only departures from standard construction are introduced in the subtracting 5 or "balance" counter S and consist, first, of a notched disk 312^x secured to the side of each numeral wheel controlling the locking mechanism; and second, the introduction of a "ring shield" 313, the object of which is 10 to shield or cover up temporarily the notch in the disk 312^x attached to the numeral wheel of greatest denomination, when charging the meter. As both of these features have been described and claimed in detail 15 in Pitney's companion application filed July 12, 1922, Serial No. 574,427, it is unnecessary to further explain same herein.

As shown, the meter 300 has a hollow metal base 301, (Figs. 12, 14, 15, 16), the bottom of which is left open until after 20 assembling of the parts therein and is then closed by a slidible plate 302 which is locked in position by an inaccessible catch 303, see Fig. 15. The base 301 is adapted to be slid 25 on the bracket 202 until its back wall touches the front wall of the box 201. The side flanges on bracket 202 are engaged by nuts 301^x on the base 301 and prevent either vertical or lateral movement of the meter; and 30 a key operated bolt 320 to be described later, holds the base 301 in close contact with the end wall of box 201 until the coupling 306 of the register drive shaft 305 in the meter is in mesh with the coupling 35 213 on the drive shaft 212. A frame 304 containing the two counters A and S and their gears is mounted on the top of the base 301, and the driving shaft 305 of the register passes through a wall 301^x at the back of 40 the base 301 which extends up above the top of said base. A metal casing 300 having glazed openings through which the readings of the counters can be seen is secured to the base 301 and encloses the registering 45 mechanism. This casing 300 is provided with a hinged door 300^a fitted with a lock and seal, the key for which would be held by the post office officials, when the machine is used for postmarking and stamping mail 50 matter. This door must be opened to set or "charge" the meter at the post office where it is locked and sealed again.

The drive shaft 305 has secured to its outer end a coupling member 306 adapted 55 to engage the coupling member 213 on shaft 212. The ratchet 307 is fast to shaft 305 and is adapted to be engaged by a pawl 309, see Fig. 14, pivotally mounted on the wall 301^x to prevent the meter drive shaft being 60 turned in a reverse direction. A cam 308, see Figs. 14, 15, 16 and 18, on the shaft 305 is adapted to be engaged by a locking pawl 310, which automatically engages the cam 308 when the subtracting counter has 65 reached zero; and also to be engaged by a

key operated locking lever 311, see Figs. 16 and 18, which engages cam 308, only when meter is removed from the machine. Either one of these members (310 or 311) engaging the cam 308 will effectually prevent the 70 shaft 305 being turned to operate the meter.

On the inner end of shaft 305 is a pinion 305^a which meshes with a gear 312, pivoted on a stub shaft between the counters and to this gear 312 is fixed a smaller gear 312^b 75 which meshes with an idler gear 312^c meshing with gear 312^a operatively connected with the units wheel of the adding counter A; and gear 312^b meshes directly with a 80 gear 312^d operatively connected with the units wheel of the subtracting counter S (see Figs. 14 and 16). The gearing is such that a half revolution of the shaft 305 will move the units wheel of both counters one 85 tenth of a revolution.

A locking comb lever 314, see Fig. 15, provided with upwardly projecting comb-like teeth 314^a, is pivoted to lugs 304^a on the counter frame 304. The teeth 314^a are 90 adapted to contact with the locking disks 312^x attached to the numeral wheels. The locking comb lever 314 is normally pressed upward by springs 314^b, (Fig. 15). The notches in the locking disks 312^x are so located that the related teeth 314^a of the comb lever 314 will engage the notches when the related numeral wheels show "0" at the sight 95 opening in the meter case 300.

When all the numeral wheels locking the 100 meter show "0" at the sight opening the teeth 314^a of comb lever 314 will have engaged the notches in the related locking can disks 312^x, and locked the register, lever 314 being raised by springs 314^b when the 105 notches permit. The locking comb lever 314 has a plate 314^c secured to its side and moving with it, said plate having a downwardly projecting lug 314^c and an outwardly projecting lug 314^d. The lug 314^d serves as 110 a handle to depress the lever 314, when charging the meter. The lug 314^c depends into the path of lever 315 and acts as a 115 catch to obstruct the movement of the forwardly extending arm 315 of a crank lever, 120 which is pivoted at 315^a on the base 301 below the counter frame 304. The other arm 315^b as shown in Fig. 17, of the bell 125 crank lever 315 projects from its pivot toward the wall 301^x of the base 301 and is provided with a head 315^c whose outer face is curved on an arc concentric with the pivot 315^a. In the head 315^c is a socket 315^d which, when the meter is "charged" is in alignment with the hole 301^x in base 301, 130 in which is entered the "meter pin" 208, hereinafter referred to (Figs. 12, 14, 15, and 17). On the arm 315^b is a boss 315^e (see Figs. 16, 17 and 18) which supports the lower arm 310^a of the locking pawl 310,

holding the pawl out of contact with the cam 308 of the drive shaft 305, when the meter is charged.

A spring 315^s (Figs. 14 and 17) attached to the arm of the bell crank lever 315 pulls it normally toward the left and holds said arm in contact with the downwardly projecting lug 314^c of the locking comb 314, and thus normally holds the arm 315^b in such position that the socket 315^d in its head 315^e is in line with hole 301^b.

The action of the levers just described in locking the meter when its subtracting counter has reached zero is as follows:

When all the numeral wheels representing dollars in the counter S reach "zero" the notches in the locking disks 312^x are all engaged by the teeth 314^a of the locking comb lever 314, which then rises (as described in the aforesaid application) to the limit and in so doing moves lug 314^c out of the path of the arm of the bell crank lever 315 which is then rocked by the pull of its spring 315^s, to the position shown in dotted lines in Fig. 17. This movement of the lever moves boss 315^e from under the arm 310^a, and the locking pawl 310 under the pull of its spring 310^s will engage one of the shoulders 308^a of the cam 308 on drive shaft 305 at the completion of the operation.

This movement of arm 315^b shifts the head 315^e, so that the socket 315^d therein no longer registers with the hole 301^b in the wall 301^a and thus prevents the re-entry of the meter pin 208.

As the release of lever 315 by the action of the locking comb 314 may occur near the beginning of a printing operation, it will be necessary to defer the rocking of lever 315 until the end of the operation. This is accomplished by the meter pin 208 (Fig. 17) which being engaged in the socket 315^d of the lever arm 315^b prevents spring 315^s rocking lever 315, until at the end of the printing operation, when the pin 208 is withdrawn; but immediately upon its withdrawal the lever 315 is rocked by its spring 315^s and the meter pin 208 cannot again enter the meter until the parts have been re-set.

Means for setting the meter.

Where the machine is used for stamping prepaid postage on letters, when the registering meter is locked as above described the machine cannot be effectively operated until the meter is removed from the machine and the registering mechanism re-set. That is, the subtracting counter in the registering mechanism must be again adjusted to show the total amount of prepaid postage purchased, say for example \$1000. For this purpose the meter is removed from the machine and taken to the post office, where the

post office official breaks the seal and unlocks the door 300^a of the meter and re-sets or charges it as follows:

In order to restore the lever arm 315^b to its normal position it is necessary to lift the locking pawl 310. To accomplish this a hand operated bell crank lever 317 (Figs. 17 and 18) is pivoted at 317^a on the floor of the counter frame 304. When the front arm of this lever is moved to the right (Fig. 15) the end of its rear arm 317^b engages a pin 310^b (Fig. 18) on the locking pawl 310 and moves the pawl out of engagement with cam 308 and raises its lower arm 310^a permitting the lug 315^c on lever 315 to be again moved under said arm 310^a, to hold the pawl 310 disengaged from the cam 308. A spring 317^s returns the lever 317 to normal position (Fig. 17) after the above operation.

After lever 317 is pushed to the right, releasing pawl 310, as described, lever 315 is then pushed to the right, returning arm 315^b supporting pawl 310 to the position indicated in full lines in Fig. 17, and bringing socket 315^d into register with opening 301^b. Comb lever 314 is then pulled down by means of handle 314^d and lug 314^c holds lever 315 in normal position (full lines as shown in Fig. 17). The ring shield 313 is then turned to cover the notch in locking disk 312^x of the numeral wheel (as described in Pitney's application, Serial No. 574,427 aforesaid) and prevents the comb tooth lever from rising. This holds the register set, as the comb lever teeth 314^a cannot again enter the notch in the last numeral wheel locking disks 312^x until all the numeral wheels have again been turned to zero. The shield 313 covering the slot in the locking disk is removed when the related numeral wheel has been turned a fraction of a revolution, permitting the locking comb to lock the numeral wheels the next time that all the wheels read zero at the dial, as described in the aforesaid application.

Means for locking the meter in position.

Secured to the front wall of the box 201 (Figs. 5, 6 and 12) is a key operated lock enclosed in a casing 223; the function of this lock is to operate a bolt 225 (Fig. 6) which can be projected into the space between the wall of the box 201 and a flange 208^a on the meter pin 208 to prevent the meter pin being moved outward sufficiently to release the machine for an operation. A cam 224 is secured to the "plug" 222^a of the lock, said cam being in the form of a "Geneva stop" and is adapted to shift the bolt 225 to either "up" or "down" position. When in the "up" position the upper end of the bolt is entered between collar 208^a on the pin 208 and the wall of the box 201 and the meter pin 208 is held in its "in" position locking the machine; when bolt 225 is in its "down" po-

sition (Figs. 12 and 17) the meter pin 208 is of bolt 322 when the meter is in place on free to be moved outward and release the the bracket as indicated in Fig. 12.

Automatically locking the printing mechanism by the meter.

The lock is enclosed in the casing 223 which projects from the front wall of the box 201 (Figs. 3 and 4) into the path of the meter. A hole 301^c, Fig. 15, is bored into the back wall 301^a of the metal base 301 to accommodate the lock casing 223, so that 10 when the meter 300 is slid into operative position on the machine it will enclose the casing 223 and the lock will then be entirely within the base of the meter.

A cylindrical plug 318, Fig. 15, having a 15 circular flange 318^a (which flange is not concentric with the plug) is slidably mounted in the hole 301^c of the base 301, said flange 318^a fitting the hole in the end wall of the meter adapted to be entered 20 by casing 223, but the axis of the cylindrical plug 318 is considerably below the center of the hole 301^c. The plug 318 is slidably supported in an opening on a bracket 319 secured in the base 301. A 25 hole 301^d is bored in the front wall of the base 301 in line with the hole in bracket 319, and a rod 320 extends through the hole 301^d and enters a hole 318^b in plug 318, and has securely fastened to its inner end a key 321. 30 Key 321 engages a key way 318^e in the bore of plug 318 which permits the plug 318 to move longitudinally of the rod 320 but forces it to turn with the rod. The outer end of rod 320 is preferably flattened as at 35 320^a to form a handle by which it may be manually turned. A collar 320^b secured to the rod 320 inside the base 301 prevents the rod being pulled outward. An expansion spring 320^c strung on the rod 320 between 40 collar 320^b and the plug 318 normally pushes the plug outward and holds flange 318^a in position to close hole 301^c, the outward movement of the plug being arrested by stop pins 318^d which engage bracket 319, when the 45 outer face of the flange 318^a is flush with the outside of the back wall 301^a of the meter base 301. The plug has a projection or tooth 318^e close to the flange 318^a, and this tooth and adjacent part of the plug 50 are shaped to form a "Geneva stop" as indicated in Fig. 18, which stop is engaged by the lower end 311^b of a lever 311 pivoted at 311^a and extending downward through an aperture in the base 301, its lower end lying 55 close to the face of the bracket 319; and machined to gear with the plug 318 and tooth 318^e, as indicated in Figs. 15 and 18.

Within the meter base is another vertical bolt 322 (Figs. 15 and 16) sliding in a 60 groove 119^a in bracket 319, and held in place by a plate 319^b. This bolt has a Geneva tooth notch 322^a machined in its side and adapted to gear with the tooth 318^e on plug 318. The bottom of the meter case 301 is 65 slotted to permit passage of the lower end

70 of bolt 322 when the meter is in place on the bracket as indicated in Fig. 12.

The control of the printing mechanism by the meter is accomplished through the action of the meter pin 208. This meter pin 208, as shown in Figs. 3, 12 and 17, is slidably mounted at the front end of the box 201 in 75 an opening 201^c in the front end wall thereof and an opening in a plate 260 fastened to the said wall by bolts or studs 261, Figs. 3 and 12. The meter pin is cylindrical in form and has two collars 208^a near its central portion. 80 Its outer end protrudes through the opening 201^c and through an opening in a boss 201^d; and the rear end of the pin is adapted to protrude inwardly through the opening in plate 260, when the meter pin is in its inner position. The meter pin can be slid back and forth axially, motion being imparted to it by a rock arm 207 whose free end 85 engages the pin 208, between the two flanges 208^a.

90 The rear end of meter pin 208 which protrudes through plate 260 is adapted to engage a slot 214^a in a disk 214 secured to the adjacent end of shaft 211, and when engaged therewith (see Figs. 3 and 12) effectually prevents any revolution of the printing die. Meter pin 208, enters this slot 214^a at the completion of every revolution of the shaft 211, and prevents shaft 211 from again revolving until and unless pin 208 is first withdrawn from slot 214^a by suitable mechanism, preferably as hereinafter described.

95 Before any printing can be done by the machine it is necessary to move the meter pin 208 outward to release the disk 214. When disk 214 begins to revolve it holds pin 208 in its out position, until, at the completion of its revolution, the slot 214^a in the disk 100 again registers with the pin, whereupon the latter will again enter the slot, said disk 214 making one revolution for each complete cycle of operations of the machine, or each effective printing operation of the machine.

105 The rocker arm 207 is pivoted at 207^a (Figs. 6 and 13) and a rod 8 is pivoted at one end to arm 207 by the pin 207^b; said rod 8 extends through holes in the frame 205 and its other end protrudes through an opening in the back wall of the box 201 (Fig. 3) and contacts with the free end of another rock arm (see Figs. 10 and 11).

110 The rocker arm 7 is attached to the upper end of a rod 7^a which is journaled in bearings on the table 200 of the machine, and extends below said table into the gear casting and is provided on its lower end with an arm 7^b which arm is connected by a link 6, Figs. 3 and 10, which is connected to one arm 5^a of a three armed lever pivoted on a 115 120 125 130

stud 5^c in the base adjacent the clutch 11 which is adapted to drive the shaft 237. The lever 7 is normally impelled inwardly so as to cause the rod 8 to swing the arm 207 to move the meter pin 208 outward by means of an expansion spring 9 confined in a casing 9^a attached to the top of plate 200 and lever 7 is moved outwardly by the action of the cam 11^c on the clutch (see Fig. 10) and at the proper time rocks the three-armed lever 5^a, this clutch being constructed and operated substantially as described in the Pitney Patent #1,360,668, above referred to.

15 A spring 8^s, Fig. 5, on rod 8 acting between the wall 205^s of frame 205 and a collar 8^a secured to rod 8 pushes rod 8 rearwardly into firm contact with end of rock arm 7. This causes rock arm 207 also to rock to its rear position, carrying with it the meter pin 208, which will thus be urged to enter slot 214^a of disk 214, whenever the slot is in position to receive it, which is always when the machine is at rest. When however under 20 the trip action, the rock arm 7 is released by rod 6, the spring 9 being much the stronger, overcomes the resistance of spring 8^s and rocks the arm 7, which pushes rod 8, rocking arm 207, thereby sliding meter pin 208 forward and releasing the printing mechanism.

This forward motion of the meter pin 208 can only be accomplished when the meter is in position on the machine and "charged" 25 to record the imprints as will be explained later. Any obstruction placed in the way preventing the meter pin 208 from being slid forward will prevent the rock arm 207, the rod 8, the rock arm 7, the rod 6, and 30 the three-armed lever 5 from being moved and as a consequence the clutch 11 will fail to act as a driver for the entire mechanism.

The shaft 237 is rotated by mechanism substantially as described in the aforesaid 45 Pitney patent, for driving the printing member therein, and is controlled by the trip devices such as described in said patent, which trip mechanism is released each time a letter passes through the machine, so 50 that the machine will perform one cycle of operation, and make one impression and register the amount of each letter which passes through the machine, the shaft 237 making one revolution for each letter passed 55 through the machine.

Shaft 237 is provided with two keys 237^a preferably integral with the shaft, which run its entire length except at the extreme top end where the shaft is journaled in the 60 bushing 237^d of the overhead bearing plate 203. A cylindrical piece 237^e (Fig. 3) is key slotted and pinned to its lower extremity and constitutes the lower journal bearing in a bracket 201^x which is secured to box 201. 65 The piece 237^e is machined at the bottom to

fit the floating ("Oldham") coupling 20 which is in turn connected with one member of the clutch 11 of the machine.

A key slotted sleeve 237^b (Fig. 8) surrounds the shaft 237 where it bears in the 70 bushing 237^e at the top of the box 201.

The action of the clutch 11 (Figs. 3, 10 and 11) acting in conjunction with a tripping mechanism is such that only one complete revolution of shaft 237 and die holder 238 75 can be made for each piece of mail fed to the machine, the revolving parts being brought to a definite stop at the same place each time a piece is printed. The impression roller 137 however is continually in 80 motion and as the printed piece must be moved along after the printing is done, an idler roller 239 is mounted on the die holder 238, Figs. 3 and 9, in such a position that it will make contact with and be frictionally driven by the impression roller 137 during the periods when the die holder 238 is at rest. The idler roller 239 is fastened to a short spindle 239^b which revolves in the arms 238^c and 238^d of the die holder 238, 85 Figs. 3 and 9. It is cut away in the central portion of its periphery at 239^a to avoid contact with the inking roller when die holder 238 is revolved.

The trip mechanism.

Referring more particularly to Figs. 1, 10 and 11, rollers 21 and 22 are a pair of rollers commonly called trip rollers, between which the letters are successively 100 passed from the feed table. The trip roller 22 is preferably journaled in a swingable support and guard 15, and is normally yieldingly pressed toward the roller 21 by a suitable spring, as indicated in Fig. 1. The shaft of the roller 21 is mounted in fixed 105 bearings opposite the roller 22 and guard 15, and a fence or guide 16 is arranged beside and between the rollers 21 and 22, but is slotted to accommodate the rollers 21 and 22 so as not to interfere with their contact with a letter passing between them.

A trip finger 1 is pivoted on a spindle 27 and has a curved head or end 1^a which projects in the path of a letter passing between 110 rollers 21 and 22, so that such a letter will strike this trip finger and will oscillate spindle 27. To spindle 27 is pinned an arm 2, and the trip finger 1 and arm 2 oscillate 115 or move as one piece. The trip finger is normally held in letter engaging position by a suitable spring, such as indicated at 28, (Fig. 11) arm 2 being arrested by a stop pin 29 when the trip finger is in normal position.

The arm 2 is adapted to engage the curved and notched end 3^a of a trip link 3 which end is supported and guided in a grooved member 13 having upper and lower disk 120 like portions 13^a which guide the end of the 130

link 3 and prevent perpendicular movement thereof, and the center portion 13, when engaged by the curved end of the link 3 forces it out of engagement with the arm 2 at the proper time. The trip link is normally held in position to engage arm 2 and the shank of member 13 by a spring 20^a Fig. 10. The other end of trip link 3 is pivoted to one arm 4, see Figs. 3, 10 and 11, of a stop lever pivoted on a stud 4^a; and arm 4 is normally held against a stop 18 by means of a spring 19, and thus holds the trip link normally retracted.

The stop lever 4 (Fig. 10) has an arm 4^b which normally projects into the path of the arm 5^a of the three-armed lever pivoted on a stud 5^c, adjacent clutch 11, and when in normal position a roller on the arm 5^a contacts with a roller on the arm 4^b and arrests the movement of the arm 5^a, which is normally pressed toward the arm 4^b by means of the link 6 under action of the spring 9.

The triple lever, of which arm 5^a forms a part, has an arm 5^b which normally projects into the path of the finger 11^a of the clutch release member of clutch 11 mounted on a shaft 30, which shaft is below and in alignment with shaft 237, and constantly driven by a gear 30^a fixed thereon and meshing with the usual train of driving gearing in the machine (not shown) so as to be constantly rotated when the machine is in operation; such gearing being well known it is not necessary to show or describe same herein.

The clutch 11 is preferably a so-called "roller clutch", of known construction and it is unnecessary to describe the same herein except in its particular relation to the working of this machine; the finger 11^a of the clutch release member protrudes from the body of the clutch in position to be engaged by arm 5^b. A stop 11^b on the clutch casing is also adapted to engage arm 5^b and take up the shock of the stoppage of the clutch and parts affected thereby.

The clutch 11 is normally disengaged from the shaft 30 by contact of its controlling finger 11^a with the arm 5^b, and the triple lever is held in this disengaging position so long as arm 4^b arrests the movement of arm 5^a. When the part 11^a is moved back toward 11^b it renders the clutch inoperative. The lug 11^b relieves the comparatively light piece 11^a from every other duty except releasing the clutch rollers.

The triple lever (having arms 5^a, 5^b) also has an arm 5 carrying a roller adapted to engage a cam 11^c on the clutch case; which cam engages the arm 5 and returns the triple lever to its original position so that arm 5^b will stop the clutch after it has completed one revolution. Rebound of the clutch and

parts connected therewith is prevented by 65 a pawl 12.

As stated, the foregoing clutch and trip devices are constructed and operated substantially as described and disclosed in the Pitney Patent #1,370,668 and are not 70 claimed herein, and therefore do not need any more detailed explanation or illustration herein.

Summary of operation.

Assuming that the parts are in operative position, as indicated in the drawings, and the meter properly "set", if a letter passes between the rollers 21 and 22 it engages the trip finger 1, rotating shaft 27, causing finger 2 to operate link 3 and oscillate lever 4 and move arm 4^b (Fig. 10) out of the path of the arm 5^a of the triple lever which, under the action of spring 9, is oscillated to release the outer portion of the clutch 11 which is 80 immediately revolved through the influence of the continuously running gear 30^a, and this imparts through the described clutch devices one complete rotation to the shaft 237 and printer carrier 238, but the movement 90 of the shaft 237 is arrested at the completion of one revolution by reason of the arm 5^b of the triple lever having been returned to position to engage and arrest the moving member of the clutch by the action of the 95 cam 11^c, as above described. During the rotation of shaft 237 the printer carrier 238 is caused to make one revolution and an impression is made from the outermost face 240^p of the die 240 upon the letter as it 100 passes the impression roller 137. This rotation of the shaft 237 imparts like rotation to shaft 211; and shaft 211, through the described gearing imparts rotation to the shaft 212 in accordance with the denomination 105 of the printing face of the die, as above described, so that the registers in the meter are caused to shift a number of units corresponding to the denomination of the stamp on the printing face of the die.

If the operator desires to change the denomination of the stamp to be printed he stops the machine and then by depressing knob 242 and shaft 241 he turns die 240 on its axis until the desired printing surface 115 is brought to the point 240^p, Fig. 9, as above described; and in making this adjustment shaft 247 is also turned and through the train of gears 248, 250, 253, 254, shifts the inking mechanism so that the ink supply, 120 corresponding in color to the denomination of stamp to be printed, is brought into position to ink the die printing such stamp. Also by the same movement through the gears 250, 251 and link 252, the gear shift 125 206 is moved longitudinally of shafts 212, 211, thereby bringing the proper set of gears 218—218^a, or 217—217^a or 216—216^a into

driving relation between the shafts 211 and 212, so that at the next printing operation the proper extent of rotary movement will be imparted to the shaft 212 to turn the register numeral wheels a number of units corresponding to the denomination of the stamp to be printed as above explained. These adjustments are all automatically performed. The printing operations can be continued until the amount of prepaid postage is exhausted, as explained in the aforesaid Pitney patent and application which is when the unit wheels in the subtracting counter S have been turned to zero at which time the locking comb plate 314 will be engaged with the notched disk 313, and whereupon the registering mechanism will be locked, as above described. Simultaneously, the lever 315 is released and shifted by spring 315^a, so that head 315^c is moved to bring the socket 315^d out of register with the hole 301^b in casing 301, and therefore the meter pin 208 is held in its "in" position, which through the described connections, rod 8, lever 7, and link 6, holds the arm of the triple lever 5^a in position to engage and arrest the clutch 11, so that although the shaft 30 continues to rotate no motion can be imparted to the shaft 237. At the same time the catch lever 310 engages the cam 308, and thus further rotative movement of the registering mechanism or meter shaft 305 is prevented. The meter must be removed from the machine and reset before the parts can again be operated.

To remove the meter the rod 320 must be turned so as to lock the lock 222^a and in this movement the tooth 318^e on lock 318 moves lever 311, so that it is engaged with the cam 308 (see Fig. 16), and upon further rotation of the shaft 320 the Geneva gear 224^a on the locking cylinder operates the lock bar 225 and projects this bar between the collar 208^a on meter pin 208 and the end wall 201, thereby preventing the meter pin from being projected when the meter is removed from the machine. Tooth 318^e also during such rotation of the plug 320 engages the notch in bolt 322 and disengages it from the slot in casting 202^x, by retracting the bolt into the meter casing. The meter may then be removed from the machine, but remains locked and the registering mechanism therein cannot be reset until it is taken to the post office, opened and set by the proper official, as above described, and when the meter is removed from the machine the machine is kept inoperative or ineffective by the bar 225 holding the meter pin 208 in retracted position, thus preventing movement of the arm 207 and keeping the clutch mechanism disengaged, as described, and further because the inner end of the pin 208 in retracted position, is engaged with disk 214 on shaft 211 and thus

said shaft is held locked, being thus provided with a double lock to prevent operation of the machine when the meter is removed. When the meter is removed from the machine the plug 318 is forced outward by spring 320 to the position shown in Fig. 15, and the disk 318^a closing the opening 301^c in the casing 301 which is occupied by the locking casing 223 when the meter is in the machine. When the meter is placed in the machine the locking casing 223 enters the opening 301^c in the casing, forcing the plug 318 inward to the position shown in Fig. 12, and then the key 321 properly engages the locking tumblers and by turning rod 320 the lock is turned and with it the Geneva gear 318^e and cam 224. In this movement the Geneva gear 318^e first projects bolt 322 into engagement with the notch 202^x locking the meter in position on the plate 202 and then engages the lever 311^b and oscillates said lever so as to disengage tooth 311 from the cam 308, and simultaneously the Geneva cam 224 engages the lock bar 225 and removes it from the path of the meter pin 208, which is then free to be operated by the machine so that when the trip 1^a is oscillated by the passage of a letter the clutch 11 will be released and the machine will perform one cycle of operations as above described. When the meter is set by the post office the locking comb 314 will have been disengaged from the numeral wheels 312^x and held disengaged by the member 313 as above explained, and the part 317^b of lever 317 will be operated to disengage the tooth 310 from the cam 308, said tooth being held disengaged as above explained until the locking comb is again released. But the meter will be held locked after its setting by the engagement of lever 311 with the disk 308 until the meter is placed in the machine and said lever disengaged by turning the locking rod 320 as above explained.

What we claim is:

1. In mechanism of the character specified, having a printing die having a plurality of printing surfaces and adjustable on its own axis to bring any one of such surfaces to printing position; an inking mechanism, and means whereby when the die is adjusted the inking mechanism is adjusted, so that each die surface will be supplied with ink of its own distinctive color.

2. In mechanism of the character specified, a printing member comprising a rotatable support, a longitudinally movable spindle mounted on said support, a die on said spindle having a series of printing faces, said die being adjustable by rotating the spindle, and means for holding the die in adjusted position; a rotatable shaft in axial alinement with the die spindle

130

when the latter is in die adjusting position, and means for interengaging the spindle and said shaft whereby the shaft is turned by and with the spindle in rotatably adjusting 5 the die.

3. In combination with mechanism as set forth in claim 2, means whereby impressions may be taken from that surface of the die which is turned to operative position on the 10 support; and means for inking that surface of the die from which impressions are taken in its own distinctive color.

4. In mechanism of the character specified, a printing member comprising a rotatable support, a longitudinally movable spindle mounted on said support, a die on said spindle having a series of printing faces, said die being adjustable by rotating the spindle, and means for locking the die 20 in adjusted position, a rotatable shaft in axial alignment with the die spindle when the latter is in die adjusting position, means for interengaging the spindle and said shaft whereby the shaft is turned by and with the 25 spindle in rotatably adjusting the die; an inking mechanism and gearing between said inking mechanism and said shaft whereby when the die is adjusted the inking mechanism is correspondingly adjusted, so that 30 each die surface will be supplied with ink of its own distinctive color.

5. In mechanism of the character specified, a printing member comprising a rotatable support, a longitudinally movable 35 spindle mounted on said support, a die on said spindle having a series of printing faces, said die being adjustable by rotating the spindle, and means for locking the die in adjusted position; a rotatable shaft in 40 axial alignment with the spindle when the latter is in die adjusting position, means for interengaging the spindle and shaft whereby the shaft is turned by and with the spindle in rotatorally adjusting the die; a 45 registering mechanism, means for operating the registering mechanism once for each operation of the die, and means operated by said shaft whereby when the die is adjusted on its axis the registering mechanism is 50 automatically adjusted so that the register will be actuated in accordance with the numerical value of the impression taken from the die.

6. In mechanism of the character specified, a printing member provided with a plurality of printing surfaces any one of which may be brought to operative position; means for taking an impression from the printing member once for each operation of the machine; a registering mechanism; means for actuating the registering mechanism once for each effective operation of the printing member including a set of variable speed gears, and means whereby when the print-

ing surface is changed the variable speed 65 gears are so adjusted that the registering mechanism will be actuated in accordance with the numerical value of the impression to be made by the printing member.

7. In mechanism of the character specified, 70 a printing member provided with a plurality of printing surfaces, any one of which may be brought to operative position; means for rotating the printing member once for each operation of the machine, a 75 registering mechanism, a shaft for actuating the register mechanism; a second shaft; gearing for rotating the second shaft once for each effective operation of the printer; a set of variable speed gears transmitting 80 motion from one shaft to the other; and means whereby when the printing surface is changed the variable gearing is adjusted so that the register actuating shaft will be 85 actuated in accordance with the numerical value of the impression to be made by the die.

8. In mechanism of the character specified, 90 a printing die having a plurality of printing surfaces, a rotatable support for the die; and said die being adjustable on its own axis on said support to bring any one of the surfaces to operative position; and means coating with that surface of the die which is turned to operative position to take 95 impressions therefrom, means for rotating the support once for each printing operation, a registering mechanism, a shaft for actuating said registering mechanism, a second 100 shaft, and means for rotating the second shaft once for each operation of the printer; said means including variable speed gears and means whereby when the printing surface is changed the variable speed gears are 105 so adjusted that the registering mechanism will be actuated in accordance with the numerical value of the impression to be made by the die.

9. In mechanism of the character specified, 110 a printing member provided with a plurality of printing surfaces, any one of which may be brought to operative position; means for taking an impression at each effective operation of the machine from the printing surface in operative position; a shaft, and means for actuating the said shaft once for each operation of the printing member, said means including a set of variable speed gears and devices whereby when the operative 115 printing surface is changed the variable speed gears are so adjusted that said shaft will be actuated in accordance with the numerical value of the impression made by the operative printing surface; with a registering mechanism adapted to be operated by said shaft, and devices controlled by the registering mechanism whereby when the said mechanism has registered a predetermined num- 120 125

ber or amount the said shaft is locked against further rotation, thereby preventing further effective operations of the printing member.

10. In combination a printing die having a plurality of printing surfaces of different denomination and adjustable to bring any one of such surfaces to printing position; means for rotating the die through an orbit for each operation thereof; a registering mechanism; means for operating the registering mechanism for each operation of the die; and means whereby when the die is shifted to change the surface from which an impression will be taken the register actuating mechanism is automatically shifted so that the register will be actuated in accordance with the impression taken from such surface.

11. In combination with mechanism of the character specified, a printing die having a plurality of printing surfaces, a rotatable support for the die, means coacting with that surface of the die which is turned to operative position on the support whereby impressions may be taken therefrom; and means for inking the surface of the die which is in operative position; means whereby when the die is adjusted the inking mechanism is adjusted so that each die surface will be supplied with ink of its own distinctive color.

12. In mechanism of the character specified, a removable meter containing a printing die having a plurality of printing surfaces; a rotatable support for the die; said die being adjustable on its own axis on said support to bring any one of the surfaces to operative position; means for rotating the support to move the die through an orbit to take an impression therefrom; and means coacting with that surface of the die which is turned to operative position to take impressions therefrom; and means for inking the surface of the die which is in operative position with ink of its own distinctive color.

13. In mechanism of the character specified, a printing member comprising a rotatable support, a longitudinally movable spindle mounted on said support, a die slidably but not rotatably mounted on said spindle having a series of printing faces, said die being adjustable by depressing and rotating the spindle, and means for holding the die in adjusted position on the support, substantially as described.

14. In mechanism of the character specified, a printing member comprising a rotatable support, a longitudinally movable spindle mounted on said support, a die slidably but not rotatably mounted on said spindle having a series of printing faces, said die being adjustable by depressing and rotating the spindle, and means for holding the die in adjusted position on the support, a register, means for operating the register for each

printing operation of the die; and means whereby when the die is shifted to change the surface from which the impression will be taken the register will be actuated in accordance with the denomination of the impression printed by such surface. 70

15. In mechanism of the character specified, a printing member comprising a rotatable support, a longitudinally movable spindle mounted on said support, a die on said spindle having a series of printing faces, said die being adjustable by rotating the spindle, and means for holding the die in adjusted position on the support, means for inking the die; and means whereby when the die is adjusted the inking mechanism is automatically adjusted so that each die surface when brought to operative position will be supplied with ink of its own distinctive color. 75

16. In mechanism of the character specified, a plurality of printing surfaces and means to bring any one of such surfaces to printing position; an inking mechanism, and means whereby when the printing surfaces are adjusted the inking mechanism is adjusted so that each printing surface will be supplied with ink of its own distinctive color. 80

17. In mechanism of the character specified, a printing member provided with a plurality of printing surfaces, any one of which may be brought to operative position; means for rotating the printing member once for each operation of the machine; a registering mechanism; a shaft for actuating the registering mechanism; a second shaft; gearing between the die rotating means and the second shaft for rotating the second shaft once for each effective operation of the printing member; sets of variable speed gears slidably mounted on said shafts for imparting motion from one shaft to the other, and means for shifting said gears from and by the adjustment of the die so that motion will be imparted from the second shaft to the register shaft in accordance with the numerical value of the impression made by the die. 85

18. In mechanism of the character specified having a rotatable support; and a printing member rotatably mounted upon said support provided with a plurality of printing surfaces; said member being adjustable so as to bring any one of said printing surfaces into operative position; a common register for said printing surfaces; means for holding the printing member in adjusted position on the support and means controlled by the adjustment of the printing member whereby the common register is actuated for each operation of the printing member in accordance with the value or denomination of that printing surface which has been adjusted to operative position. 115

19. In a machine of the character speci- 130

- 5 fied, having a rotatable support, a printing member mounted upon said support and having a plurality of printing surfaces adjustable so as to bring any one of such surfaces into operative position, and means for holding the printing member in adjusted position; a single register and means controlled by the adjustment of the printing member whereby the register is subtractively 10 actuated for each operation of the printing member in accordance with the value or denomination of that printing surface which has been adjusted to operative position.
- 15 20. In mechanism of the character specified, a printing member, and means for taking an impression therefrom, a shaft, and means for actuating said shaft once for each operation of the printing member; of a registering mechanism adapted to be operated by said shaft; a pin, means for reciprocating this pin at each effective operation of the machine; and a disk on the shaft adapted to be engaged by the pin to lock said shaft, substantially as described.
- 25 21. In a machine of the character specified, having a rotatable support, and a die mounted upon said support having a plurality of circumferentially arranged printing surfaces and adjustable on its own axis 30 to bring any of its segments to printing position, and means for rotating the support to take an impression from the segment in printing position; a register, variable gearing, and means whereby the adjusting of the 35 dies causes the gearing to be varied so that the register will be operated in accordance with the denomination of the adjusted die.
22. In a machine of the character specified, having a frame and a support rotatably mounted upon said frame, and an adjustable die carried by said support having a multiple of printing surfaces and adapted to be adjusted to bring any of its printing surfaces to printing position; and means for rotating the support and means cooperating 40 with the die when the support is rotated to take an impression from the surface in printing position; a register; variable gearing, and means whereby the adjustment of the die causes the gearing to shift so that 45 the register will be operated at each rotation of the support in accordance with the denomination of the adjusted printing surface.
23. In mechanism of the character specified having a rotatable support, a multiple 50 printing die mounted on the support and adjustable on its own axis and having a plurality of circumferentially disposed printing surfaces, means for adjusting the die on its axis to bring any one of its printing surfaces to operative position at the periphery of the support, and means for rotating the support to take impressions from the die; a register, gearing for operating the register units wheel at each rotation of the support; 55 and variable gearing whereby the adjustment of the die will shift the gearing so as to cause the units wheel of the register to be moved at each rotation of the support in accordance with the denomination of the adjusted die.

In testimony that we claim the foregoing as our own, we affix our signatures.

ARTHUR H. PITNEY.
JACOB W. OGDEN.
